GAME AND GAME APPARATUS

Robert A. Gorsuch, Gambier, Ohio

Application April 11, 1942, Serial No. 438,626

2 Claims. (Cl. 273—127)

This invention relates to games and game apparatus, and more particularly to games of the kind that may be played upon lawns or other suitable playing surfaces.

The invention was inspired by the game of shuffle board, although its only similarity thereto is in the action of the players and the general scheme of scoring.

The primary purpose of the invention is to provide a game affording all the recreational benefits of shuffle board, and possessing additional features of interest, without requiring expensive cement or other hard surface courts such as are essential to the game of shuffle board. Cement courts are practical only in climates having little or no freezing weather, and accordingly games requiring such courts are confined in their use to certain localities. The game of my invention, on the other hand, is suited to any locality, regardless of climate, and may be played on any reasonably good strip of lawn or other readily available playing surface about 10 feet wide and 36 feet long. The playing surface need not be absolutely level but is satisfactory if it is such as would be adapted to croquet or roque, for example.

Another object of the invention is to provide a goal marker that is especially convenient of placement on a lawn or other playing surface and which is made up of pieces of rope or the like, suitably connected together by simple and inexpensive means, and in such manner and arrangement as to facilitate manufacture and handling.

Another object is to include in a game of the sort to which the invention pertains a feature that enhances the excitement and interest of the game and which consists in supporting, in a certain place with respect to the goal, as upon a seat within and desirably at the center of the space enclosed by the marginal goal line, a displaceable target member, or, in more limited terms, a free object ball, which is adapted to be dislodged from said place or seat by a player and to assume a plus or minus counting position within the goal, thus increasing or decreasing the player's score by a value according to the position in which the target member or object ball comes to rest, said member or ball being returned to its place or seat immediately after said value is noted so that the next player may have an opportunity to dislodge it, as will hereinafter more fully appear.

A further object of my invention is to provide a playing implement or cue for propelling or

shooting the playing members or balls and which is relatively simple and inexpensive of construction; is strong and durable, and which cooperates with a ball in such manner as to reduce to a minimum the friction between the implement and ball.

A still further object is to provide an implement or cue of the character set forth that is so shaped or constructed that it may be employed with facility for retrieving, maneuvering or carrying a ball.

The foregoing objects, with others hereinafter appearing, are attained in the embodiment of the invention illustrated in the accompanying drawings wherein Fig. 1 is a diagram showing the general character and relation of the goal markers, with the displaceable target members or object balls in normal or seated position, and indicating a desirable arrangement of the playing members or balls for shooting; Fig. 2 is a perspective view of one of the goal markers as it would appear in use, with playing members or balls scattered about thereon in positions they might occupy at the end of a play, and with the target member or object ball dislodged from its seat; Fig. 3 is an enlarged detail of the central portion of the goal marker including the seat for the target member or object ball; Fig. 4 is a perspective view of the implement or cue for propelling or shooting the playing members or balls, the view showing the implement applied to a ball in readiness for shooting; Fig. 5 is a bottom plan view of the head portion of the implement or cue, the ball being indicated in broken lines in this and the succeeding view; Fig. 6 is a central longitudinal section through said head portion; Fig. 7 is a sectional detail on the line 7—7 of Fig. 6; Fig. 8 is a view of the sheet metal blank from which the body portion of the head is constructed, and Figs. 9 and 10 are views illustrating how the implement or cue may be employed for retrieving or maneuvering a ball, and for carrying a ball, respectively.

The game, in its present preferred form, includes two goal markers, each about 4' square that are adapted to be arranged upon a lawn or other suitable playing surface about 21' apart, as indicated in Fig. 1.

Each goal marker is designated generally by the reference numeral 1, and it is desirably constructed in most part of rope about the size of that ordinarily used for clothes lines. Obviously, tape or other material might be employed in place of rope, or, so far as the game, generally, is concerned, the goals might be defined by lines

or stripes made upon the playing surface. The linear elements of the goal marker will herein be referred to as lines. Each goal marker includes a marginal line 2 which, when straightened out in the position it occupies when the device is in use, defines a square. Extending inwardly from the corners toward the center of said square are diagonal lines 3. In the present construction, two linear elements make up the four diagonal lines and one end of each of said elements is connected to the marginal line at one of the corners of the square, in a manner hereinafter to be described, and is carried toward the opposite diagonal corner until it closely approaches the center of the square, when it is turned laterally and back to a corner intermediate the aforesaid diagonal corners. These two linear elements are connected together at about the center of the square by parallel links 4, shown in Figs. 2 and 3, and which are desirably made of lengths of wire having their ends hooked over and pinched about said linear elements. These links, with the portions of the elements that extend between them, form the seat for the target member or object ball, as will hereinafter appear. This makes a cheap and highly satisfactory construction although equivalent arrangements and constructions are embraced within the scope of my invention.

At each corner of the square defined by the marginal line 2, parts of said line, with the outer end of the adjacent diagonal line 3 are gathered together and securely fastened by suitable means 5 which desirably consists of a stiff wire clamping ring or winding. The portions of the line 2 outwardly beyond the fastening means 5 form loops 6. Staples 7 are adapted to be engaged through the loops 6 and driven into the ground for holding the goal marker firmly in place. An intermediate line 8 intersects the diagonal lines 3 and the parts thereof between adjacent diagonal lines are parallel to the corresponding parts of the marginal line.

In playing the game, two sets of playing members or balls are used. Each set preferably consists of three playing members or balls, and those of one set are suitably distinguished from the playing members or balls of the other set, as by being of a different color. Said members or balls of the two sets are designated 10 and 11, respectively, and are indicated as being colored red and blue. They are shown in Fig. 1 in their desired shooting positions in readiness, for example, for the first play of a game, although they are similarly arranged adjacent first one goal and then the other for the succeeding plays. In describing the manner in which the game is played, it will be assumed that four persons are participating. For convenience, they may be referred to as players A, B, C and D. Their playing positions are indicated by the location of said letters in Fig. 1 and the players A and B are partners, as are the players C and D.

Occupying the beforementioned place or seat at the center of each goal marker is a displaceable target member or object ball 12 that is suitably distinguished by color or otherwise from the playing members or balls. To carry out a patriotic intent, they are preferably white, since the playing members are red and blue. By means of the implement or cue presently to be described, the player A shoots one of the playing members or balls 10 toward the distant goal and desirably at the target member or object ball 12 associated therewith. The space enclosed by the marginal

line 2 of each goal marker is divided into sections by the diagonal lines 3 and intermediate line 8, and the scoring values of said sections are indicated by the numerals shown in dotted lines in Fig. 1. The players A and C take turns shooting until all members or balls 10 and 11 of the two sets have been shot at the opposite or distant goal. If during the shooting the target member or object ball 12 is displaced from its seat and lodges within the limits of the goal, an amount determined by the plus or minus scoring value of the space in which the member or ball comes to rest is noted for addition to or subtraction from the score of the player responsible for dislodging said member or ball. Immediately after noting said amount, the member or ball is returned to its place or seat so as to give the next player an opportunity on his next shot to score in like manner. After the two players A and C have shot all the playing members or balls of their respective sets, their scores are figured according to the positions of said playing members or balls, and the play which has just been completed constitutes a half-frame. The results of this half-frame are recorded or inscribed on a suitable scoreboard or sheet, tally, or the like.

At the end of a play or half-frame, the balls might occupy some such positions as are illustrated in Fig. 2, it being assumed that the balls approached the goal marker in the direction of the arrow, and that the object ball 12 was dislodged from its seat by the last ball shot, which might be the blue ball lying nearest the seat. By referring to the left hand goal of Fig. 1, the scoring values of the various sections of the goal may be ascertained, as previously explained. The score, therefore, according to the arrangement of the balls in Fig. 2, is 10 for the "reds"—that is, for partners A and B, who are using the red balls; and 15 for their opponents, the "blues", or partners C and D. In estimating the score of the "blues," the 10 gained by the dislodgment of the object ball 12 into the rear adjacent 10 space is cancelled by the blue ball that lodged in the "10-Off" space. The present frame is completed when players B and D, taking turns, return the playing members or balls of their respective sets to the goal at the left of Fig. 1.

In the second frame, the blues shoot first; in the third frame, the reds, and so on until the game is completed. The side first scoring 100 points (or more) at the end of any half-frame wins the game. In the case of a tie, extra half-frames are played until the tie is broken. When two persons play the game, the two players shoot alternately from the first goal to the second, and then from the second back to the first, and so on.

The objects of each player are: to stop each ball he shoots in the most favorable scoring position; to drive his opponent's ball out of scoring position—that is, beyond the marginal line of the goal, or into the "10-Off" space; and to dislodge the target member or ball from its seat and cause it to assume a position in which it will add the maximum amount to his score. In general, it is well to aim at the target member or object ball and try to hit it just hard enough to topple it from its place or seat into an adjacent "10" section.

The implement or cue used for propelling the playing members or balls along the playing surface, as well as for retrieving, maneuvering and carrying the ball, is illustrated in Figs. 5 to 10. It comprises a handle 20, desirably made of wood,

and a head designated generally by the reference numeral 21. The head is made up of a body portion 22 and a yoke 23, and incorporates an anti-friction element or roller 24. The body portion 22 is formed from the blank of sheet metal illustrated in Fig. 8, where said blank is designated 22^a. The yoke 23 is preferably made of heavy, stiff wire and is generally U-shaped, and the rear end portions of its lateral branches are turned inwardly and upwardly at a slight angle to the forward parallel portions thereof and are snugly held within sleeves provided by the curled over edges of the body portion 22 that are formed from the parts 22^b of the blank 22^a. The end portions of an axle 25 by which the anti-friction element or roller 24 is rotatably supported are grasped within transverse sleeves formed by the curled under forward edges of the body portion 22 (constituted of the parts 22^c of the blank) and located on opposite sides of a notch 26 in the forward end of the body portion and which notch accommodates the element or roller 24.

The handle 20 is provided with a transverse kerf at its forward end into which the central part of the body portion 22 is inserted, the kerf being deep enough to allow the body to enter until a lug 27 engages the front end of the handle, said lug being formed by a part 22^d of the blank 22^a. A screw or other fastening means 28 is then driven into the handle and through an aperture in the body portion 22. This aperture may be preformed or not, as desired, its position being indicated at 22^e on the blank 22^a of Fig. 8. A simple but very effective connection between the head and handle is thus formed, the handle, at the rear of the head, being confined between the ends of the sleeves that embrace the rearwardly converging parts of the yoke 23, while it is otherwise held in fixed relation to the handle by the fastening means 28 and the lug 27. The forward end of the yoke 23 is arched upwardly and over between the lateral branches thereof, as best shown in Fig. 4.

When it is desired to shoot a playing member or ball, such as that designated 10 in Figs. 4 to 6, 9 and 10, the yoke is dropped over the ball until its lateral branches rest upon the ball slightly above the center thereof. The anti-friction element or roller 24 engages the rear side of the ball in about the plane of the yoke (Fig. 6) and spins as the ball is propelled along the playing surface by means of the implement. The element

or roller 24 is preferably of the ball-bearing type and rotates very freely, wherefore friction is reduced to a minimum. This end is further served by the fact that only a very slight portion of each lateral branch of the yoke engages the ball at any time, and then quite near the rotating axis of the latter. In taking a shooting position, the player stands with his arm hanging at his side and, if right handed, comfortably grasps the rear end portion of the handle 20 in his right hand, and engages the head of the implement with the ball, as illustrated in Fig. 4. The player then steps forward, leading with his left foot, and swings his right arm as he steps forward with a long even stroke. Obviously, a left handed player reverses the above described position. As the player reaches the end of the stroke, the implement is lifted from the ball, such action being enhanced by the tendency of the roller 24 to ride up the ball as the stroke is concluded.

In retrieving or maneuvering a ball, the implement may be turned over and used in the manner shown in Fig. 9; and a ball may be flipped or rolled onto, and carried by the implement, as illustrated in Fig. 10.

Having thus described my invention, what I claim is:

1. A goal marker constructed of flexible linear elements including a marginal line which, when laid out in operative position, encloses a rectangular space, diagonal lines extending from the corners to approximately the center of said space, the outer end of each diagonal line, and parts of the marginal line adjacent thereto being fastened together in such manner as to provide loops outwardly beyond the junction of the marginal and diagonal lines.

2. A goal marker constructed of flexible linear elements including a marginal line which, when laid out in operative position, encloses a rectangular space, diagonal lines extending from the corners to approximately the center of said space, the outer end of each diagonal line, and parts of the marginal line adjacent thereto being fastened together in such manner as to provide loops outwardly beyond the junction of the marginal and diagonal lines, and an intermediate line intersecting the diagonal lines and having the parts thereof between the diagonal lines approximately parallel to the sides of said space.

ROBERT A. GORSUCH.
